UNITED STATES PATENT OFFICE.

PHILIP J. CONBOY AND JAMES A. MURPHY, OF HAMILTON, OHIO.

JARRING-MACHINE.

950,893.

Specification of Letters Patent. Patented Mar. 1, 1910.

Application filed September 16, 1909. Serial No. 518,028.

To all whom it may concern:

Be it known that we, PHILIP J. CONBOY and JAMES A. MURPHY, citizens of the United States, residing at Hamilton, Ohio, have invented a new and useful Improvement 5 in Jarring-Machines, of which the following is a specification.

Our invention relates to jarring machines of the class adapted for use in foundries for packing the sand in the flasks and around the patterns, and the objects of our improvements are to provide means for adjusting the length of the stroke of the piston; to provide a plural number of compression 10 chambers; to provide means for utilizing either or all of said chambers simultaneously; to provide emergency exhaust passages for limiting the stroke of the piston; to provide an anvil of very much greater 15 diameter than the piston, and to provide simple and durable construction and assemblage of parts for securing facility of operation and efficiency of action. These objects are attained in the following described manner as illustrated in the accompanying drawings, in which:—

Figure 1 is a vertical transverse section of a jarring machine embodying our improvements; Fig. 2, a side elevation with parts 20 broken away, and Fig. 3, a longitudinal section of the valve box and connections.

In the drawings, 1 represents a cylindrical column having its end portions of different diameters and separated by an offset or edge 25 2 at an intermediate point in its length. The smaller upper portion 3 of said column is formed with a concentric expansion chamber 4 in its top and with an emergency exhaust opening 5 through its side wall a 30 short distance above the closed bottom 6 of said chamber. A cylinder 7 having its opposite end portions formed of different diameters to correspond with the respective large and small portions of the column is slidably 35 mounted thereon. Said cylinder is also formed with a depending piston 8 adapted to reciprocate within the expansion chamber 4 and with an annular expansion chamber 9 between its wall 11 and the piston 8 adapted 40 to slidably engage with the annular top wall 12 of the column which encircles the pressure chamber 4. An annular flange or foot 13 formed on the bottom of the cylinder 7 serves to contact with the anvil 14 which 45 may consist of fibrous or other suitable material. A superposed platen or table 15

secured on the cylinder in any manner desired is provided on one of its edges with a depending flange 16 which is formed with a horizontal slot 17. A rock shaft 18 mounted 50 on a stand 19 is provided with a crank 21 and with a slotted arm 22. A bolt 23 which pivotally connects said arm to the flange 16 may be adjusted in different positions on both the flange and the arm. 55

A connecting rod 24 connects the crank 21 with the plunger 25 which is slidably mounted on the valve casing 20 and whereon tappets 26 and 27 are adjustably secured. Said casing is formed with an inlet chamber 28, a pressure chamber 29 and an exhaust chamber 31. The inlet and exhaust chambers communicate respectively with the supply and the exhaust pipes 32 and 33. Inlet and discharge valves 34 and 35 are moved and maintained under a yielding pressure in the closed position by means of the respective springs 36 and 37. An arm 38 hinged at one end on the casing and actuated by contact of tappet 26 at an intermediate point thereon 40 is arranged to contact at its other end with the end of the projecting stem 39 of the exhaust valve for imparting a quick opening movement thereto. 75

The tappet 27 serves to open the inlet 85 valve by contacting with the end of the projecting stem 41 thereof. The tappets on the plunger 25 may be properly adjusted for permitting the valves to be alternately and securely seated by the corresponding 90 spring before the other valve is opened. Pipes 42 and 43 each provided with a shut off cock 44 lead from the pressure chamber 29 to the respective expansion chambers 4 and 9. 95

Emergency exhaust openings 45 and 46 formed in the wall of the cylinder 7 are adapted to register simultaneously with the respective openings 5 and the top of the column 1 for exhausting the expansion 100 chambers at a predetermined elevation of the cylinder on the column.

In operation, for light loads on the table the cock may be opened in the pipe leading to the small expansion chamber 4, for medium loads the cock may be opened in the pipe leading to the expansion chamber 9 which is preferably in cross-sectional area about double that of chamber 4, for extra heavy loads the cocks in both pipes may be opened for utilizing both expansion chambers simultaneously. At a predetermined 105

elevation of the cylinder on the column the connections therewith actuate the plunger with the corresponding tappet thereon to suddenly move the arm and fully open the exhaust valve that the cylinder may quickly descend and contact with the anvil. The descent of the cylinder actuates the same connections to permit the sudden closing of the exhaust valve and to open the inlet valve more gradually for forcing the cylinder in an upward direction again. By means of the adjustable connection of the slotted arm with the table flange, the stroke of the cylinder may be increased or diminished as desired without otherwise changing its connections with the valves. The emergency exhaust ports prevent the cylinder from exceeding a predetermined elevation on the column.

20 What we claim is:

1. A jarring machine comprising a plural number of expansion chambers, pistons therein, inlet passages communicating with the respective chambers and separate valves for independently controlling said passages.
2. A jarring machine comprising a plural number of expansion chambers of different capacities, pistons movable simultaneously in relation thereto, a table movable with one of the pistons, passages communicating with the respective chambers, valves for controlling said passages and connections with the table for actuating the valves.
3. A jarring machine comprising a column consisting of superposed cylinders of different diameters and formed with an expansion chamber in its upper portion, a counterbored cylinder arranged to slidably engage with the column and formed with a piston and with an annular expansion cham-

ber concentric therewith adapted to slidably engage with the upper portion of the column, passages communicating with said chambers from a source of air under pressure, valves for controlling said passages simultaneously and connections with the counterbored cylinder for operating the valves.

4. A jarring machine comprising a column, a cylinder slidably engaging therewith and inclosing a plural number of expansion chambers between them, said column and cylinder being provided with emergency exhaust openings for the chambers, passages communicating with the respective chambers, valves for controlling said passages, and adjustable connections with the cylinder for automatically operating the valves.

5. In a jarring machine, the combination of a reciprocating table, a plunger, adjustable connections of the table therewith whereby the length of the stroke of the table may be changed in relation to that of the plunger, and separate inlet and exhaust valves actuated successively and independently by the plunger.

6. A jarring machine comprising concentric cylinders, pistons therein the one of said pistons and cylinders being movable in relation to the corresponding piston and cylinder, pipe connections between said cylinders and a source of liquid under pressure, valves for controlling said connections, and means actuated by the movable piston for operating the valves.
